FENCE CLIP FASTENING TOOL
Harlan J. Easton, Box 607, Blooming Prairie,
Minn. 55917
Filed Mar. 22, 1965, Ser. No. 441,655
1 Claim. (Cl. 140—123)

ABSTRACT OF THE DISCLOSURE

A fence clip fastened tool having a single handle with a jaw formed at one end thereof and a second jaw pivotally attached thereto for normally encompassing a clip, and, upon engagement with a fence post and pivoting action therearound, forming the clip to fit the post. Each of the jaws has a clip receiving groove therein, and the jaws are biased into a clip retaining position by a spring.

This invention pertains to an improved fastening tool for attaching the horizontal wire of fences to a metal fence post with a small wire fence clip and more particularly to an improved tool which maintains a fence clip therein until ready for use and which substantially prevents lateral movement of the clip within the tool thereby minimizing the loss of clips as well as insuring a positive and uniform bend in the clip about the fence post.

In prior art fence clip fastening tools a handle bar having one end curved to extend around one edge of a metal fence post and a pivotally attached hook member curved to extend around the other edge of the fence post cooperate to form clip-bending jaws. To utilize this tool a clip is inserted into the jaws and the jaws and clip are held with one hand while one jaw and one end of the clip are engaged about one edge of the fence post and the other end of the clip and the pivotal jaw are placed in position at the other edge of the fence post. The handle is then pivoted about the fence post to bend the clip in place. However, since these prior art tools have nothing to prevent the clip from moving laterally, in many instances the clip will simply slide out laterally and not bend and in many instances the clip will slide partially out whereby the bend in all of the clips will not be uniform and optimum. Also, these prior art devices are very cumbersome since there is nothing to retain the clip between the jaws and the one jaw is free to pivot relative to the other jaw until the tool is engaged about a fence post, thus requiring an operator to use both hands throughout the clip fastening operation.

In the present invention a handle bar with a curved portion adapted to extend around one edge of a metal fence post has an inner surface or edge along the bight of the curve which forms a first clip-bending jaw. A groove at the tip of the jaw receives one end of the fence clip and substantially prevents lateral movement thereof. A hook member is pivotally attached to the handle bar and has an inner surface or edge along the bight of the curve which forms a second clip-bending jaw. In operation the first jaw and the second jaw cooperate to bend the clip into the desired form about the fence post. A plurality of grooves in the surface of the second jaw or hook member maintain the clip rigidly in position between the jaws and substantially prevent lateral movement thereof. A tension spring having one end fixedly attached to the handle bar and the other end fixedly attached to the end of the hook member opposite the curve biases the hook member so that the jaws are normally in a clip-retaining position.

Thus, a fence clip fastening tool is disclosed which securely retains the clips between fence fastening operations and during the fastening operation. Also, the new

2

and improved tool prevents lateral movement of the clip during the fastening operation whereby the clips are all bent uniformly and loss of clips etc. is minimized.

It is a further object of the present invention to provide a fence clip fastening tool which securely holds the clips and prevents loss thereof or improper bending.

It is a further object of the present invention to provide a fence clip fastening tool which securely holds the clips between fence fastening operations whereby the tool may be used with one hand leaving the other hand free to place clips therein.

These and other objects of this invention will become apparent to those skilled in the art upon consideration of the accompanying specification, claim, and drawings.

Referring to the drawings, wherein like characters indicate like parts throughout the figures:

FIG. 1 is an elevational view of the present invention, illustrated in the clip-fastening position in dotted lines;

FIG. 2 is an edge view of the present invention;

FIG. 3 is an elevational view of the side opposite to that shown in FIG. 1, parts thereof broken away;

FIG. 4 is a sectional view as seen from the line 4—4 in FIG. 1;

FIG. 5 is a sectional view as seen from the line 5—5 in FIG. 1; and

FIG. 6 illustrates a clip fastened to a metal fence post, the dotted lines illustrate the clip in the unfastened position.

In the figures the numeral 10 designates a handle bar having a curved end portion 11 attached thereto by some means such as rivets 12 or the like. It should be understood that curved portion 11 could be an integral portion of handle bar 10 and is shown as a separate portion for simplicity of construction. The curved portion 11 is adapted to extend around one edge of a metal fence post designated 13. The metal fence post 13 has a T-shaped cross section with a vertical, approximately flat portion 16 of the fence post 13 forming the cross arm of the T. A metal clip 14 is engaged with the flat portion 16 of the fence post 13 by bending both ends around the edges thereof.

In FIG. 6 the fence post 13 is illustrated with a clip 14, shown in full lines, securely engaged thereto. A fence wire 15, shown broken away, is woven between the clip 14 and the fence post 13 whereby the wire 15 is securely fastened to the fence post 13. The clip 14 in an unbent or unfastened state is illustrated in FIG. 6 in dotted lines. The unfastened clip has one end 17 which is doubled over in approximately a 180° angle to extend around one edge of the fence post. The other end 18 of the clip has a bend of approximately 90° the same distance from the end. The two bends are spaced apart on the clip a sufficient distance to allow the flat portion 16 of the fence post 13 to lie therebetween.

Again referring to the tool the curved portion 11, which is somewhat C-shaped and has one end fixedly attached to the handle bar 10, has a groove 20 at the opposite tip thereof which is adapted to receive the end 18 of clip 14. The groove 20 at the tip of the curved member 11 is formed by fixedly attaching a U-shaped portion 40 to the tip of the curved member 11. The tip of the curved member 11 is fitted into the bight of the U-shaped portion 40 so that a part of the U-shaped portion extends past the end of the tip, thereby forming a groove at the end of the tip having a U-shaped cross section. The groove 20 has a depth approximately equal to the radius of the clip 14 so that the edges of the groove do not interfere with bending of the clip 14 snugly against the fence post 13 while they substantially prevent lateral movement of the end 18 of the clip 14 within the tool.

A hook-shaped member 25 is pivotally attached to the curved member 11 by some means such as rivet 26. The

hook member 25 is composed of three pieces, 35, 36 and 37 sandwiched together in that order. The three pieces 35-37 are fixedly attached to each other by some means such as welding or the like. The pieces 35 and 37 are hook-shaped duplicates and the piece 36 sandwiched therebetween has approximately the same thickness as the curved member 11. The hook-shaped member 25 is attached to the curved member 11 so that the ends of the two members form cooperating jaws.

The bight or the inner curved surface, which is designated numeral 30, of the hook-shaped member 25 is shaped to fit snugly over the end 17, including the 180° bend, to clip 14 when it is forced into the fastening position about the edge of the portion 16 of fence post 13. To securely fasten the clip 14 to the fence post 13 the fastening tool is rotated a sufficient distance to force the end 17 of clip 14 and the edge of the fence post 13 into the bight of the hook 25. This insures a uniform bend at the end 17 of clip 14 and forces the end of the clip tightly against the back of the flat surface 16 of the fence post 13.

The inner surface 30 in the bight of the curve forming the hook member 25 has a plurality of grooves therein for receiving the clip 14 prior to the fastening operation. A first groove 31 at the tip of the hook member 25 engages the clip 14 near the end 17 after the 180° bend. A second groove 32 engages the clip 14 near the 180° bend but in the midsection of the clip 14. A third groove 33 engages the clip 14 near the end 18 but before the 90° bend in the midsection of the clip 14. It should be understood that the grooves 20, 31, 32 and 33 are positioned in what is considered the most advantageous portions of the clip but could be moved to different portions of the clip and, if a different type of clip is utilized, a different number of grooves may be desirable.

To form the grooves 31, 32 and 33 portions of the central piece 36 of hook member 25 are ground away, or removed in some similar fashion, leaving grooves formed between the pieces 35 and 37. The thickness of the part 36 and the curved member 11 is slightly greater than the diameter of the clip 14 so that the clip 14 fits easily into the grooves 31, 32 and 33 while lateral movement of the clip 14 is substantially prevented.

A tension spring 45 has one end connected to the handle bar 10 by means of an L-shaped member 46. L-shaped member 46 is connected to the handle bar 10 by one of the rivets 12. The other end of the tension spring 45 is connected to an L-shaped member 47 which is fixedly attached to the hook-shaped member 25. The L-shaped member 47 is attached to the hook-shaped member 25 by some means such as welding etc. at the 45 end of the member 25 opposite the hook. The pivotal mounting rivet 26 connects the hook-shaped member 25 to the curved member 11 between the L-shaped member 47 and the bight of the hook. With this attachment the tension spring 45 provides a bias on the hook-shaped member 25 tending to rotate it clockwise in FIG. 3 which is into a clip-retaining position or a closed-jaw position.

In the operation of the present tool the hook member 25 is rotated clockwise in FIG. 1 until the clip 14 can be placed between the jaws. The hook-shaped member

25 is then released and the tension spring 45 rotates it to the clip-retaining position. The end 17 of the clip 14 and the bight of the hook-shaped member 25 are then placed about one edge of the fence post 13 and pressure is applied to the handle bar 10 in a downward direction, in FIG. 1, until the tool assumes the dotted position. In this position the end 18 of clip 14 is bent into snug engagement with the other edge of the flat portion 16 of fence 13 and the end 17 is bent into snug engagement with the first edge thereof. The tool is then removed by rotating it counterclockwise past the original position. A new clip 14 may then be placed in the jaws of the tool and it will be retained there, through the action of tension spring 45, until the operator is ready to use it.

Thus, a new and improved fence clip fastening tool is disclosed in which lateral movement of the clip is substantially prevented whereby loss of clips and nonuniform bending is eliminated. Also, because of the clip-retaining features the present tool is much easier to operate than the prior art devices.

While I have shown and described a specific embodiment of this invention, further modifications and improvements will occur to those skilled in the art. I desire it to be understood, therefore, that this invention is not limited to the particular form shown and I intend in the appended claim to cover all modifications which do not depart from the spirit and scope of this invention.

I claim:

1. A fence clip fastening tool comprising:

- (a) a single handle bar with a curved portion at one end thereof adapted to extend around one edge of a metal fence post;
- (b) said curved portion having an inner surface in the bight of the curve forming a first clip-bending jaw;
- (c) a groove in the tip of said first jaw for receiving one end of a fence clip and substantially preventing lateral movement thereof;
- (d) a hook shaped member pivotally attached to the curved portion of said handle bar to extend around the other edge of said fence post;
- (e) said hook shaped member having an inner surface in the bight of the curve forming a second clip bending jaw for cooperating with said first jaw;
- (f) clip-receiving grooves in said inner surface of said hook shaped member for engaging said fence clip at a plurality of points along said clip and substantially preventing lateral movement of said clip; and
- (g) spring biasing means connected to said handle bar and said hook shaped member for biasing said first and second cooperating jaws in the clip-retaining position.
